UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

MULTIPLEX REPRODUCING

Application filed May 3, 1929. Serial No. 360,068.

The present invention relates to multiplex transmitting and receiving systems, and is particularly directed to a method and means by which signals corresponding to facsimile and television signals may be simultaneously reproduced along a plurality of distinct paths. It has long been known in the art to which the invention relates that, if it is possible to simultaneously transmit a plurality 10 of distinct lines of a facsimile or a television subject, the speed and efficiency of transmission can be considerably increased and the time element for transmitting and receiving a picture or television system may be considerably reduced.

As has been disclosed in my copending application, Serial No. 360,066, filed May 3, 1929, I have provided a method and means by which a facsimile message or a television 20 subject may be simultaneously analyzed along a plurality of adjacent or even separate paths, and the present invention is particularly directed to a receiving system for use in conjunction with an analyzing system of the type 25 disclosed in the said copending application.

As a primary object of my invention, I have, therefore, sought to develop a method and means by which a plurality of distinct light paths may be traced upon either a light 30 sensitive recording medium in case of facsimile or picture transmission, or upon a screen, or the like, in conjunction with television transmission.

Still another object of my invention is to 35 provide a method and means by which the separation of the individual light paths for recording is produced.

Still other objects of my invention are to provide, in a method to be hereinafter set 40 forth, an arrangement for tracing a plurality of light paths corresponding to the intensity of light and shadow on elemental areas of a facsimile or television subject which is relatively simple in its construction and arrangement 45 of parts, a system which is compact, conveniently installed, easily set up, readily operated, and efficient in its use.

Further and ancillary objects of my invention will at once suggest themselves and 50 become apparent to those skilled in the art

to which the invention relates from a consideration of the drawings forming a part of my present disclosure when said drawings are read in conjunction with the following specification and claims.

By Fig. 1 of the drawings, I have illustrated an arrangement for tracing a pair of individual light paths either along a light sensitive record or upon a screen; and,

By Fig. 2 of the drawings, I have illustrated a system whereby five distinct lines or paths of light may be traced, supposing that the system is applicable to a five channel multiplex communication system.

It is, however, to be understood that while the invention has been illustrated as being applied to only two and five channels of multiplex communication that the invention is not limited thereto but that the number of channels may be any desired and suitable 65 number without diverting from the spirit and scope of my invention.

Also, while the receiving circuits operate in conjunction with transmission circuits, such as have been disclosed in certain of my 70 copending applications, particularly applications, Serial No. 269,099, filed April 11, 1928; Serial No. 309,274, filed September 29, 1928; and Serial No. 349,076, filed March 22, 1929, for example, it is to be understood that 75 the receiving circuits operating in conjunction with the arrangement herein disclosed may embody the usual type of receiving and amplifying system working in conjunction with suitable and proper filters for distinguishing between the different tone frequencies used and provide for separating the various light bands, the output of which may then be directed to any proper form of indicating system.

Also, as the invention has herein been illustrated as being applied particularly to radio transmission, it is nevertheless likewise applicable to wire or wired radio systems, and by use of the term "radio", I wish to include 85 all types of known communication systems. Likewise, the term "pictures" as herein used should be interpreted in a generic sense so as to include, television subjects, motion picture films, views, photographs, newspaper 90

articles, magazine covers, checks, finger prints, fashion plates, legal documents, financial statements, code messages, messages in foreign languages, and the like.

5 Now referring more particularly to the drawings forming a part of the present disclosure, signals from the various filtering systems set forth in the above named copending applications may be directed to appropriating forms of glow lamps, such as the general type shown and described in connection with copending application, Serial No. 350,922, filed March 29, 1929, by R. M. Williams, or any other well known type of illumination 10 means such as an ordinary electric lamp and the like.

Referring first to Fig. 1 of the drawings, the signal energy received from the various filtering systems corresponding to the separate tones produced in the transmission of the multiplex message is directed to each of the glow lamps, 1 and 3 respectively, in which a glow corresponding to the intensity of light and shadow on elemental areas of the picture 20 surface is produced. As has been shown, the glow issuing from the lamps 1 and 3 is then projected in a longitudinal direction therefrom so as to pass through a diaphragm arrangement 5 or 7. The diaphragm may be 25 adjustable along axes at right angles to each other so that the size of the openings 9 and 11 therein may be varied at will so as to increase or decrease the size thereof. Light thus projected through the openings 9 and 30 11 in the diaphragm members 5 and 7 may then be projected through lens systems 13 and 15 from which the individual paths of light are projected to right angle prisms 17 and 19 respectively.

40 The prisms 17 and 19 are preferably mounted upon brackets 21 and 23 which are adjustably mounted on any suitable and desired support means 25 and 27 so that they may be adjustable in the direction shown by 45 the arrows adjacent each of the support means. This adjustment is at times necessary so that the light which is reflected from the faces 29 and 31 of the prisms 17 and 19 respectively may be projected along the desired path so as to reach a second pair of reflecting prisms 33 and 35 from the faces 37 and 39 of which the light is again bent at right angles so as to be projected along a path designated as 41. In line with the 50 path 41, the two parallel rays of light, a' and b' , corresponding to the paths of light a and b issuing from the light sources 1 and 3 respectively, may be passed through a recording lens system 43 which is preferably 55 formed from a pair of lenses 45 and 47 arranged to have the focal point thereof arranged upon a recording surface 49 carried by a recording drum member 51 which preferably moves in the direction shown by the 60 arrow thereon. As will be seen, the light 65

beams a' and b' which pass through the lens system 43 may then be focused as two distinct and independent but nevertheless adjacent points of light 53 and 55 upon the record surface 49.

70 If the record surface 49 is made sensitive to light, it will readily be seen that light rays produced and issuing from the sources 1 and 3 will trace paths on the recording surface 49 corresponding to the elemental tones on the individual paths of the record surface as analyzed in accordance with an analyzing system of the usual type shown and described in connection with my copending application, Serial No. 360,066, filed May 3, 1929.

75 Now referring to Fig. 2 of the drawings, I have illustrated a further modification of the scheme above described in connection with the illustration of Fig. 1, wherein an arrangement capable of tracing five distinct paths of light on a record surface has been 80 illustrated.

85 To refer now more particularly to the disclosure of Fig. 2, a plurality of glow lamps or other appropriate light sources, 2, 4, 6, 8, and 10, are arranged to be independently influenced by signals received through any appropriate and desired form of multiplex receiver so as to produce, when energized, a glow in accordance with the intensity of light 90 and shadow on the particular picture surface or television subject being reproduced at the particular time. The light issuing from each of the sources, 2, 4, 6, 8 and 10, has been indicated conventionally by the letters a , b , c , d and e respectively.

95 These light beams may then be directed through a diaphragm 12 having openings 14, 16, 18, 20 and 22 therein for each of the individual light beams to pass through. While the diaphragm member 12 in Fig. 2 has not been shown as being adjustable as to the size of the various openings therein, it is, however, within the scope of my disclosure to provide adjustment in two directions in connection with this type of diaphragm so that, for example, if each of the openings are of square formation, the area of each opening may be either increased or decreased by appropriately adjusting the diaphragm member 12 from either of two directions, or may be made elongated by only adjusting the diaphragm in one direction as has been disclosed by my copending application, Serial No. 360,066, filed May 3, 1929, for example.

100 As the light beams, a , b , c , d , and e respectively, pass beyond the diaphragm member 12, they are projected respectively upon prisms 24, 26, 36, 30 and 28, which may be appropriately arranged to deflect the path 105 of the individual light beams in a predetermined and chosen manner so as to ultimately collect all of the separate beams within a relatively small space. It will be seen that the light beam a passing beyond the prism 24 is 110

directed to still a second prism 32 and therefrom projected or deflected at right angles through a glass supporting plate 42 so as to impinge upon a relatively large prism 44. 5 Similarly, light projected along the path *d* is reflected or deflected by the prism 30 against a prism 34 also carried by the glass supporting plate 42 and then directed to the prism 44. As has been shown, the light 10 issuing from the source 6 along the path *c* passes directly through a square prism 36 also carried by the glass supporting plate 42 to the prism 44. In this case, it will be noted that the light beam has not been changed as 15 to its path since, as has been shown, the light source 6 is arranged at the center of all of the other light sources, and, therefore, the light issuing from each of the adjacent sources is ultimately grouped about this particular 20 light beam. In like manner, the light issuing from the source 4 and projected along the path *b* is reflected and deflected by the prism 26 to the prism 38 and projected through the glass plate 42 to the prism 44 along the path 25 *b*, and, in like manner, light projected along the path *e* is passed through the prisms 28 and 40 as well as the glass supporting plate 42 to the prism 44.

All of the light beams, *a*, *b*, *c*, *d*, and *e* are 30 then reflected from the face 46 of the prism 44 and arranged to pass through a lens system, formed of a pair of condensing lenses, 48 and 50 respectively, so as to focus as independent points of light upon a record surface 35 face 62 carried about a supporting drum 64 turned upon its axis 66 in the direction shown by the arrow, for example. It will be seen from the accompanying drawings that the light beam *a* is projected as a point 52 on 40 the record surface 62, the light beam *d* projected as a point 54, the light beam *c* as a point 56, the light beam *d* as a point 58, and the light beam *e* as a point 60.

While I have herein shown my invention as 45 applied to recording facsimile messages, wherein the record drum 51 may be turned in the direction shown by the arrow so that the picture may be produced along a path corresponding to a helix having a pitch which is 50 determined by the desired amount of detail in the picture and also by the number of distinct and independent paths of recording, or which may be traced upon a record surface in which either the recording drum or the 55 light source for illuminating the same move relative to each other, it is also readily seen that the same principle of invention may be applied to television systems wherein the individual paths of light as projected from the 60 reflecting prisms of Figs. 1 and/or 2 may be projected through lenses, or the like, so as to trace a plurality of distinct and independent paths upon a screen and thus reproduce a television image.

65 It will also be readily understood that cer-

tain modifications and changes may be made to the invention herein disclosed, and I, therefore, desire to be limited in so far as the modifications which I may make to the system herein set forth only in so far as the spirit and scope of the hereinafter appended claims necessitates. 70

Having now described my invention, what I claim and desire to secure by Letters Patent is the following:

1. A system for reproducing pictures in multiplex transmission systems which includes a plurality of glow lamps, means for producing a glow in each of said lamps in accordance with the intensity of light and shadow on elemental areas of a transmitted picture, means for projecting the light issuing from each of said glow lamps along predetermined paths, condensing means for collecting the light beams issuing from each of said sources and confining the said beams to a predetermined illuminated area, and means for projecting each of said light beams at different adjacent points on a received record surface. 75 80 85

2. A system for reproducing pictures in multiplex picture transmission systems which includes a plurality of glow lamps for producing glow in accordance with the intensity of light and shadow on elemental areas of a picture to be reproduced, means for separating the glow issuing from said glow lamps into predetermined paths corresponding in number to the number of channels forming the multiplex communication system, means for collecting the light issuing from each of said glow lamps, means for projecting each of said independent paths of light along a predetermined path, and a single reflecting means for projecting each of said independent light beams along closely adjacent paths to a plurality of adjacent points on a surface for reproducing a transmitted picture. 90 95 100 105

3. A system for reproducing pictures in multiplex transmission system which includes a plurality of glow lamps, means for producing a glow in each of said lamps in accordance with the intensity of light and shadow on elemental areas of a transmitted picture coordinated with each of said lamps, means for projecting the light issuing from each of said glow lamps along predetermined paths, a prism in the path of all of said light beams for collecting the light beams issuing from each of said sources and confining the said beams to a predetermined illuminated area, and means for projecting each of said light beams at different adjacent points on a received record surface. 110 115 120

4. A system for reproducing pictures in multiplex picture transmission systems which includes a plurality of light sources for producing illumination proportionate to the intensity of light and shadow on elemental areas of a picture to be reproduced, a diaphragm for 125 130

separating the light issuing from said sources into predetermined paths corresponding in number to the number of channels forming the multiplex communication system, a reflecting prism for collecting the light issuing from each of said light sources, means for projecting each of said independent paths of light along a predetermined path, and a single reflecting means for projecting each of said independent light beams to a plurality of adjacent points on a surface for reproducing a transmitted picture.

5. A system for reproducing pictures as a plurality of adjacent recorded points in multiplex communication systems which includes a plurality of light sources energized in accordance with the intensity of light and shadow on elemental areas of a transmitted picture, means for confining the light issuing from each of said sources to predetermined paths, reflecting means in the path of each of said light beams for directing the said beams along predetermined paths, and a single reflecting means in the path of all of said reflected light beams for projecting all of said light beams along closely adjacent parallel paths, and means for projecting all of said light beams at adjacent points on a record surface for reproducing a picture.
